ROOF CONSTRUCTION

Filed Aug. 12, 1927

Inventor

Else Heidmann
By her Attorney
Marie Rein

UNITED STATES PATENT OFFICE.

ELSE HEIDTMANN, OF BRONX, NEW YORK.

ROOF CONSTRUCTION.

Application filed August 12, 1927. Serial No. 212,377.

This invention relates to roofs, skylights, etc., with particular reference to the construction thereof.

Such roofs as those used in motion picture studios, railroad stations, hot-houses, etc., are made of a transparent material and heretofore, obstacles have been encountered in connecting the sections of such roofs to make the same substantially water-proof.

Also, it is known that moisture from the steam liberated in such buildings collects on the roofs and after a while drops down.

It is therefore the main object of this invention to provide means whereby the several sections of a transparent roof may be connected so as to permit a minimum of water or moisture to pass therebetween.

A further aim is in the provision of means to catch and carry off any water which should find its way intermediate the sections of the roof and thus prevent the water from dropping down.

These several objects, together with others, which will become apparent as the description progresses, are accomplished by the unique construction, combination and arrangement of few and simple elements hereinafter described and illustrated in the accompanying drawing, constituting an important component of this disclosure, and in which:—

Figure 1 is a broken perspective view of an embodiment of the invention as applied to a cylindrical tubular beam.

Figure 2 is a similar view showing its application to a beam of channel section.

Figure 3 is a like view of the same as applied to a channel beam of lesser depth.

Figure 4 is a fragmentary perspective view of a slant roof made in accordance with the invention.

Referring to the drawing, the numeral 5 generally designates a plurality of plate glass sections overlapped by mullions 6, through which pass short rods 7, screw-threaded at the ends to engage a nut 8 on its upper end, engaging the top surface of the mullion, the lower end engaging a beam 9 in the form of a cylindrical tube.

Engageable on the rod 7, closely contacting the under-surface of the plates 5, is a metal plate 10, its longitudinal edges being rolled to form gutters 11, the outer edges 12 of which are curled to engage the edges of a holder 13 closely following the contour of the gutters and contacting beam 9, there being longitudinal depression 14 in the holder on each side of the rod 7, receptive of rubber strips 15 between the depressions and the plate 10.

In Figure 2, instead of using cylindrical beam 9, there is substituted a channel-shaped beam 20, its upper free edges 21 being converged to frictionally engage the inner walls of the holder 13, the resiliently converged ends being spread outwardly by the action of an inverted channel 22 engaging the lower screw-threaded portion of the rod 7.

In Figure 3 the beam consists of a channeled member 25 provided with a transverse pin 26 passing through the flattened reduced lower end 27 of the rod 7, in this case there being no threads on the lower end of the rod.

While the preferred forms of my invention have been shown and described, it is not intended that the foregoing be interpreted as limitative, as changes may be made without conflicting with the scope of the hereto appended claim.

Having thus described my invention, what I claim as new and desire to secure by Letters Patent, is:—

A water-proof roof comprising a plurality of transparent plate sections, mullions overlapping the adjacent edges of said sections, rods engaging said mullions and passing intermediate said sections, gutter plates through which said rods pass, support plates below said gutter plates, said support plates having longitudinal grooves, packing strips disposed in the grooves to contact the gutter plates, and a beam carrying said support plates and into which said rods are engaged.

In witness whereof I have affixed my signature.

ELSE HEIDTMANN.
